UNITED STATES PATENT OFFICE

WILLIAM H. MADDEN, OF MOUNT PLEASANT, TEXAS

PLOW

Application filed September 18, 1929. Serial No. 393,505.

This invention relates to plows, and more particularly to the construction of the moldboard thereof, the primary object of the invention being to provide a moldboard which 5 may be readily and easily substituted for the usual moldboard of a plow, to adapt the plow for use as a terracing plow.

Another object of the invention is to provide a moldboard which is exceptionally long, 10 so that the dirt and sod may be thrown and spread as desired while terracing.

A still further object of the invention is to provide a moldboard including a removable section which may be readily and easily positioned for use, should it be desired to throw the dirt laterally, a greater distance than 15 could be accomplished with the usual moldboard.

With the foregoing and other objects in view, which will appear as the description proceeds, the invention resides in the combination and arrangement of parts and in the details of construction hereinafter described and claimed, it being understood that changes 25 in the precise embodiment of the invention herein disclosed, may be made within the scope of what is claimed, without departing from the spirit of the invention.

Referring to the drawing:

20 Figure 1 is a perspective view of a plow equipped with a moldboard constructed in accordance with the invention.

Figure 2 is a perspective view taken at the rear of the plow.

25 Figure 3 is an elevational view of the moldboard forming the essence of the invention.

Figure 4 is a sectional view taken on line 4-4 of Figure 3.

30 Referring to the drawing in detail, the reference character 5 designates the plow stock, which is of the usual and well known construction, to which the landside 6 is secured. At the forward end of the plow is the usual plow point 7. The reference character 8 designates the moldboard of the plow, which as shown, is substantially long, the same being provided with openings to receive the bolts 9 that secure the front end of the moldboard in position.

35 50 As shown, the moldboard 8 is curved trans-

versely, in the usual manner, and extends to a point an appreciable distance beyond the rear end of the landside 6, so that the dirt and material turned over by the moldboard, will be thrown a greater distance than is possible 55 with the moldboards now in use.

Secured to the rear surface of the moldboard, is a strap 10 into which the extension 11 of the auxiliary moldboard 12 is positioned, there being provided a pin 13 extended vertically through the extension 11 and engaging the strap 10, to secure the auxiliary moldboard 12 in position.

Shoulders 14 are formed at one end of the auxiliary moldboard 12 and cooperate with 60 the pin 13 in holding the auxiliary moldboard 65 in a true horizontal position.

Thus it will be seen that by using this auxiliary moldboard, the dirt or material may be thrown a greater distance than with the 70 moldboard 8, adapting the plow for a particular use.

The usual plow beam is indicated by the reference character 15 and is provided with the usual clevis 16 by means of which the 75 power device may be hitched to the plow. The handles are indicated by the reference character 16, and are braced in the usual and well known manner as by means of the braces 17.

80 I claim:

A plow including a plow stock, an elongated moldboard secured adjacent to the plow stock, a strap extending rearwardly from the moldboard, an auxiliary moldboard having an extension at one end thereof, said extension defining shoulders to engage the strap, and a securing pin extended through the extension and engaging the strap to cooperate with the shoulders in holding the auxiliary moldboard in position.

85 In testimony that I claim the foregoing as my own, I have hereto affixed my signature.

WILLIAM H. MADDEN.
